UNITED STATES PATENT OFFICE

101,292

DESIGN FOR A PISTON PEENING MACHINE

Clyde F. Shuler, Philadelphia, Pa., assignor to
Wilkening Manufacturing Company, Philadelphia,
Pa., a corporation of Delaware

Application August 10, 1936, Serial No. 64,338

Term of patent 7 years

To all whom it may concern:

Be it known that I, Clyde F. Shuler, a citizen of the United States, residing at Philadelphia, in the county of Philadelphia and State of Pennsylvania, have invented a new, original, and ornamental Design for a Piston Peening Machine, of which the following is a specification, reference being had to the accompanying drawings, forming part thereof:

Figure 1 represents a perspective view of a piston peening machine showing my new design.

Figure 2 represents a front elevational view of the same on a somewhat smaller scale.

Figure 3 represents a left-side elevational view of the same, on the same scale as Figure 2.

Figure 4 represents a right-side elevational view of the same, on the same scale as Figure 2.

Figure 5 represents a top plan view of the same, on the same scale as Figure 2.

Figure 6 represents a section generally on lines 6—6 of Figure 2.

I claim:

The ornamental design for a piston peening machine, as shown and described.

In testimony whereof I have hereunto set my hand and seal.

CLYDE F. SHULER.
